AIR-HEATING APPLIANCE

Blaine Clyde Watts, Jr., Petaluma, Calif., assignor
to Kresky Mfg. Co., Inc., Petaluma, Calif., a
corporation of California

Application May 3, 1948, Serial No. 24,820

6 Claims. (Cl. 126—110)

1

This invention relates to heater appliances and more particularly to an improved heater appliance in the nature of a floor furnace or space heater.

A principal difficulty in the manufacture and installation of floor furnaces, particularly of the type adapted to circulate heated air from both sides of a building wall, resides in the difficulty of maintaining the top panel of the furnace housing cool—especially that part of the housing in contact with the wall in which the furnace is positioned. Inasmuch as the heated air travels upwardly within the furnace housing toward the top thereof the problem of cooling the top satisfactorily and practically has gone long unsolved.

An object of the present invention is to provide means in a heater appliance to cool parts of the housing thereof by drawing in cold air, by means of a circulation inducing mechanism, below the top of the housing and above the warm air outlet of said furnace.

It is a further object of the present invention to cool the top panel of a floor furnace with cold air.

A further object of the present invention is to maintain the top panel of a floor furnace cool by means of channeling cold air thereunder and which said stream of cold air is subsequently discharged from the furnace as heated air. Thus the cold air utilized to cool the top panel of the floor furnace is preheated prior to contact with the heating elements of the furnace unit.

A further object of the present invention is to provide a heater appliance of the character utilized to discharge warm air from opposite sides of a building wall and wherein the top panel of said furnace is maintained in a cool condition during operation of the furnace.

A further object of the present invention is to provide an improved floor furnace wherein hazard from fire caused by overheating of parts of the housing of said furnace is effectively eliminated.

A further object of the present invention is to provide an efficient heater appliance wherein very little heat is wasted by conduction through the housing or casing of the furnace unit but is instead utilized fully for the intended space heating purpose.

Further objects and advantages of the invention will become apparent upon referring to the accompanying drawings and specification in which similar characters of reference represent corresponding parts in the several views.

2

Fig. 1 is a perspective view of a dual outlet type floor furnace with portions thereof broken away.

Fig. 2 is an end elevational view of a dual outlet floor furnace installed in a building wall and showing the building floor and building wall in section.

Fig. 3 is a sectional view taken on line 3—3 of Fig. 2.

Fig. 4 is a sectional view taken on line 4—4 of Fig. 1.

Referring now to the drawings the floor furnace comprises an outer casing or housing 2 enclosing a burner unit (not shown). The type of burner unit generally utilized is of the forced draft type and a part of the burner construction is indicated at 3. The floor furnace illustrated herein is of the character adapted to be installed in a building wall and wherein heated air is emitted therefrom on both sides of the wall.

Fig. 2 illustrates an installation of the present type burner and wherein the outer casing 2 is illustrated as below the building floor indicated at 4 and 5 while the wall is illustrated at 6. A furnace head generally indicated at 7 is positioned above the furnace outer casing 2. Warm air outlets are provided in opposite sides of the head 7 longitudinally thereof and are preferably provided with louvers 8. Disposed within the head 7 is an inner head or shell, generally indicated at 10, provided with imperforate end portions 9 spaced inwardly from the ends 11 of the furnace head 7. The shell is provided with an imperforate substantially trough shaped top member 12 spaced below the imperforate top

panel 13 of the furnace head in order to form a cold air passageway or duct between said member 12 and said panel 13. Each end 11 of the head 7 is provided with a plurality of spaced cold air inlet apertures 14 arranged on each side

thereof to enable communication from atmosphere to said cold air duct. When the furnace is installed in a wall the apertures 14 are positioned on opposite sides of the wall as indicated clearly in Fig. 2. The cut-out portion of the wall

6 in which the furnace is disposed lies over and in contact with the top panel 13, and the ends of the head and the apertures 14 are arranged on opposite sides of said wall.

The casing 2 is partitioned vertically as at 20 to form a cold air inlet flue 15 at one end of the said casing. Usually the end of the casing in which the air inlet flue is positioned is opposite the burner unit 3 and blower 3^a. A circulation inducing mechanism indicated as a power fan 16 is disposed near the bottom of the casing 2 in

cold air inlet flue 15 in registry with an aperture 17 in communication with the space surrounding air heating elements 18 and 19 adjacent the bottoms thereof, and which said elements are heated by a burner unit (not shown) by conveying the hot gases of combustion from the burner unit therethrough to a chimney outlet attachment flange 31. Air entering through aperture 17 is heated by contact with elements 18 and 19 and is then discharged from the head 7 through the warm air outlets. A vertical partition 21 is provided in the head between an end 9 of the inner head and the adjacent end 11 of the outer head 7 above the circulation inducing fan 16. The vertical partition 21, disposed between louvers 8, serves to direct air entering through louvers 8 downwardly toward fan 16 for circulation.

Cold air is drawn into the furnace unit through apertures 14 disposed at opposite ends of the head, and cold air entering from the end of the furnace farthest removed from the fan 16 is conducted through the duct formed by top panel 13 and member 12 to thus cool and maintain cold said top panel 13 which would otherwise be heated directly by contact with the heated air rising from contact with the heating elements 18 and 19 for discharge through the warm air outlets provided in said furnace head. It might here be further noted that the spaces between the ends 9 and the ends 11 are filled with cold air entering through apertures 14, and thus the ends of said head 7 are maintained in a cool condition during operation of the floor furnace. Careful experiment has indicated that without the provision of the cooling duct formed by member 12 and panel 13 the temperature of the panel 13, formed of metal, during operation of the furnace approximates 90° F. above room temperature, whereas when the same furnace is equipped with the cooling duct, as herein described, the temperature of said top panel approximates only 20° F. above room temperature.

Figs. 1 and 2 illustrate by means of arrows A the flow of cold air through the cold air duct and into the cold air inlet flue of the furnace while arrows B indicate the flow of hot air and serve to illustrate the desired cooling function made possible by the present invention. It is noted that the cold air duct formed by the imperforate ends 9, ends 11 and members 12 and 13 is not in flow communication with the heated air arising from contact with the heater elements in the furnace casing.

While the invention has been described in specific detail by way of illustration and example for clarity of understanding, it is understood that various changes and modifications may be practiced in the utilization and design of the invention within the spirit of the invention and scope of the appended claims.

I claim:

1. In a heating appliance, an outer casing, an outer head comprising top, side and end walls disposed over said casing and in flow communication therewith through the bottom thereof and adapted to project from a floor into a cut-out portion of a building wall to expose the side walls of the head on opposite sides of the building walls, an air heating element in said casing and means to heat said element said element being disposed below the bottom of said outer head, means forming a vertical cold air inlet flue in and adjacent to one end said casing and in communication at its lower end with the space sur-

rounding said air heating element, warm air outlets in the side walls of said outer head, an inner head comprising a top and end walls positioned within the outer head and spaced inwardly therefrom to form a cold air duct between the tops of said inner and outer heads, and spaced apertures in an end wall of said outer head in communication with atmosphere and one end of said cold air duct, said cold air duct at its other end being in flow communication with the upper end of said cold air inlet flue.

2. A heating appliance comprising an outer casing, a head comprising top, side and end walls disposed over said casing and in flow communication therewith through the bottom thereof, an air heating element in said casing and means to heat said element, said element being disposed below the bottom of said head, means forming a vertically disposed cold air inlet flue in said casing in communication adjacent to its lower end with the space surrounding said air heating element, a warm air outlet in a side wall of said head, a member comprising a top and end walls positioned within said head and spaced therefrom to form a cold air duct between the tops of said member and said head, and apertures in an end wall of said head in communication with atmosphere and said cold air duct, said cold air duct being in flow communication with the upper end of said cold air inlet flue at a point substantially removed from said apertures in said head.

3. A heating appliance comprising an outer casing, an outer head comprising top, side and end walls disposed over said casing and in flow communication therewith, enclosed air heating elements in said casing and means to heat said elements, said elements being disposed below the bottom of said outer head, means forming a vertically disposed cold air inlet flue in said casing adjacent to one end thereof and in flow communication at its lower end with the space surrounding said air heating elements, means to induce circulation of cold air from said cold air inlet flue toward said air heating elements, a warm air outlet in the side walls of said outer head, an inner head comprising a top and end walls positioned within said outer head and spaced inwardly therefrom to form a horizontally disposed cold air duct between the tops of said inner and outer heads, and apertures in the end walls of said outer head in communication with atmosphere and said cold air duct, one end of said cold air duct being in flow communication with the upper end of said cold air inlet flue.

4. A heating appliance comprising an elongated outer casing, a head comprising top, side and end walls disposed over said casing and in flow communication therewith, an air heating element in said casing and means to heat said element, said element being disposed below the bottom of said head, means forming a vertically disposed cold air inlet flue in said casing at one end thereof and in flow communication at its lower end with the space surrounding said air heating element, means to induce circulation of cold air from said cold air inlet flue toward said air heating element, a member comprising a top and end walls positioned in said head and spaced inwardly therefrom to form a horizontally disposed cold air duct between said tops of said member and said head and longitudinally of said head, and an aperture in the end wall of said head farthest removed from said cold air inlet flue in communication with atmosphere and one end of said cold air duct, the other end of said

cold air duct being in flow communication with the upper end of said cold air inlet flue.

5. A heating appliance comprising an outer casing, an outer head comprising top, side and end walls disposed over said casing and in flow communication therewith through the bottom thereof, an air heating element in said casing and means to heat said element, said element being disposed below the bottom of said outer head, means forming a vertically disposed cold air inlet flue in one end of said casing and extending substantially from top to bottom thereof and in flow communication at its lower end with the space surrounding said air heating element, means in said cold air inlet flue to induce circulation of cold air therefrom toward said air heating element, warm air outlets provided in opposite side walls of said outer head, a member comprising a top and end walls positioned in said outer head and spaced inwardly therefrom to form a cold air duct between said tops of said member and said head, the top of said member being disposed above said warm air outlets, and spaced apertures in the end wall of said head farthest removed from said cold air inlet flue, said apertures being in communication with atmosphere and one end of said cold air duct, the other end of said cold air duct being in flow communication with the upper end of said cold air inlet flue.

6. A heating appliance comprising an elongated outer casing, an elongated outer head comprising top, side and end walls disposed over said casing and in flow communication therewith, an air heating element in said casing and means to 35 heat said element, said element being disposed

below said outer head, said casing having a vertical partition arranged to form a vertically disposed cold air inlet flue in one end of said casing and an aperture in said partition adjacent to the bottom thereof to enable flow communication from said flue to the space surrounding said air heating element, means in said cold air inlet flue to induce circulation of cold air therefrom toward the bottom of said air heating element, warm air outlets provided in said outer head on opposite sides thereof, an inner head comprising a top and end walls positioned in said outer head and extending substantially from end to end thereof and spaced inwardly therefrom to form a horizontally disposed cold air duct therebetween, and spaced apertures in the end wall of said outer head farthest removed from said cold air inlet flue, said apertures being in communication with atmosphere and one end of said cold air duct, the other end of said cold air duct being in flow communication with the upper end of said cold air inlet flue whereby cold air entering through said spaced apertures is conveyed through said cold air duct to said flue and thence for contact with said air heating element.
